(57) **CLAIM**

The ornamental design for a lighting fixture, as shown and described.

DESCRIPTION

FIGS. 1-7 illustrate a first embodiment of the lighting fixture.

FIG. 1 is a top perspective view of the first embodiment of the lighting fixture.

FIG. 2 is a bottom perspective view of the first embodiment of the lighting fixture.

FIG. 3 is a front view of the first embodiment of the lighting fixture.

FIG. 4 is a left side of the first embodiment of the lighting fixture.

FIG. 5 is a right side view of the first embodiment of the lighting fixture.

FIG. 6 is a top view of the first embodiment of the lighting fixture.

FIG. 7 is a bottom view of the first embodiment of the lighting fixture.

FIGS. 8-14 illustrate a second embodiment of the lighting fixture. The lampshade in this fixture comprises a faceted pattern that is continuous around the entire perimeter of the lampshade.

FIG. 8 is a top perspective view of the second embodiment of the lighting fixture.

FIG. 9 is a bottom perspective view of the second embodiment of the lighting fixture.

FIG. 10 is a left side view of the second embodiment of the lighting fixture.

FIG. 11 is a front view of the second embodiment of the lighting fixture.

FIG. 12 is a right side view of the second embodiment of the lighting fixture.

FIG. 13 is a top view of the second embodiment of the lighting fixture.

FIG. 14 is a bottom view of the second embodiment of the lighting fixture.

FIGS. 15-21 illustrate a third embodiment of the lighting fixture.

FIG. 15 is a top perspective view of the third embodiment of the lighting fixture.

FIG. 16 is a bottom perspective view of the third embodiment of the lighting fixture.

FIG. 17 is a left side view of the third embodiment of the lighting fixture.

FIG. 18 is a front view of the third embodiment of the lighting fixture.

FIG. 19 is a right side view of the third embodiment of the lighting fixture.

FIG. 20 is a top view of the third embodiment of the lighting fixture.

FIG. 21 is a bottom view of the third embodiment of the lighting fixture.

FIGS. 22-28 illustrate a fourth embodiment of the lighting fixture. The lampshade in this fixture comprises a faceted pattern that is continuous around the entire perimeter of the lampshade.

FIG. 22 is a top perspective view of the fourth embodiment of the lighting fixture.

FIG. 23 is a bottom perspective view of the fourth embodiment of the lighting fixture.

FIG. 24 is a left side view of the fourth embodiment of the lighting fixture.

FIG. 25 is a front view of the fourth embodiment of the lighting fixture.

FIG. 26 is a right side view of the fourth embodiment of the lighting fixture.

FIG. 27 is a top view of the fourth embodiment of the lighting fixture.

FIG. 28 is a bottom view of the fourth embodiment of the lighting fixture.

FIGS. 29-35 illustrate a fifth embodiment of the lighting fixture. The lampshade in this fixture comprises a faceted pattern that is continuous around the entire perimeter of the lampshade.

FIG. 29 is a top perspective view of the fifth embodiment of the lighting fixture.

FIG. 30 is a bottom perspective view of the fifth embodiment of the lighting fixture.

FIG. 31 is a left side view of the fifth embodiment of the lighting fixture.

FIG. 32 is a front view of the fifth embodiment of the lighting fixture.

FIG. 33 is a right side view of the fifth embodiment of the lighting fixture.

FIG. 34 is a top view of the fifth embodiment of the lighting fixture.

FIG. 35 is a bottom view of the fifth embodiment of the lighting fixture.

FIGS. 36-42 illustrate a sixth embodiment of the lighting fixture. The lampshade in this fixture comprises a faceted pattern that is continuous around the entire perimeter of the lampshade.

FIG. 36 is a top perspective view of the sixth embodiment of the lighting fixture.

FIG. 37 is a bottom perspective view of the sixth embodiment of the lighting fixture.

FIG. 38 is a left side view of the sixth embodiment of the lighting fixture.

FIG. 39 is a front view of the sixth embodiment of the lighting fixture.

FIG. 40 is a right side view of the sixth embodiment of the lighting fixture.

FIG. 41 is a top view of the sixth embodiment of the lighting fixture.

FIG. 42 is a bottom view of the sixth embodiment of the lighting fixture.

FIGS. 43-49 illustrate a seventh embodiment of the lighting fixture. The lampshade in this fixture comprises a faceted pattern that is continuous around the entire perimeter of the lampshade.

FIG. 43 is a top perspective view of the seventh embodiment of the lighting fixture.

FIG. 44 is a bottom perspective view of the seventh embodiment of the lighting fixture.

FIG. 45 is a left side view of the seventh embodiment of the lighting fixture.

FIG. 46 is a front view of the seventh embodiment of the lighting fixture.

FIG. 47 is a right side view of the seventh embodiment of the lighting fixture.

FIG. 48 is a top view of the seventh embodiment of the lighting fixture; and,

FIG. 49 is a bottom view of the seventh embodiment of the lighting fixture.

The broken lines shown in FIGS. 9, 14, 30 and 35 illustrating a circular perimeter adjacent the bottom portion of the lampshade indicate a boundary of the claimed design. The other broken lines shown on the drawings depict portions of the lighting fixture that form no part of the claimed design.
